Hayes, Middlesex, England, a company of
Great BritainApplication June 11, 1938, Serial No. 213,111
In Great Britain June 18, 1937

4 Claims. (Cl. 192—118)

This invention relates to automatic control mechanisms for gramophones and the like of the kind in which an inward movement of the tone arm or arm carrying an electrical reproducing device serves to move a lever into the path of a cam rotated by the turntable drive, the said lever being moved under the action of the said cam to its original position until an exaggerated movement of the tone arm or pick-up arm occurs when due to the consequent increased movement of the said lever the rotation of the turntable is stopped or a brake or a clutch is actuated, initiating if desired subsequent operations such as may be necessary in an automatic record changing machine. Such a control mechanism is disclosed in the specification of British Patent No. 332,004.

Control mechanism of the above kind, while being efficient from the mechanical point of view, is not in one respect satisfactory, since the intermittent engagement of the cam member with the said lever gives rise to a tapping noise which is liable to mar the reproduction of the record.

It is therefore the object of the present invention to provide an improved control means with a view to overcoming this defect.

According to the invention, a control mechanism of the kind referred to is provided in which the surface of said lever with which the cam engages (or the surface of the cam member) is formed of sound-absorbing or sound-deadening material whereby the intermittent engagement of the cam with said lever is rendered less audible, and additional surfaces are provided one of which is carried by said lever and the other of which is rotated by the turntable for co-operation to stop rotation of the turntable when an exaggerated movement of the tone arm occurs. The sound-absorbing or sound-deadening material may be constituted by a piece of leather or other suitable material. In the preferred form of the invention the lever is intermittently moved away from the surface of the cam by the engagement of the cam with sound-absorbing or sound-deadening material carried by the lever, and a lug is provided on said lever and which is engaged when an exaggerated movement of the tone arm occurs by a stop carried in a plane different from that of the cam.

In order that the said invention may be clearly understood and readily carried into effect, it will now be more fully described with reference to the accompanying drawing in which:

Figure 1 is a plan view of the preferred form of

the mechanism constructed in accordance with the invention.

Figure 2 is an end elevation of the mechanism shown in Figure 1 looking towards the left-hand end of Figure 1, and

Figure 3 is a view of the mechanism shown in Figure 1 with the parts in a different position.

In the drawing, the reference numeral 4 indicates the lever which is intermittently moved towards and away from a cam 5 formed on a 10 sleeve 6 attached to a boss 7 rotating with the turntable 8, shown in Figure 2, the lever 4 being frictionally coupled with a fork 9 which engages a lug, not shown, depending from the tone arm, also not shown, the lever 4 being capable of an 15 angular movement with respect to the fork 9 between a pair of limiting lugs 10 and 11. The surface of the lever 4 with which the cam 5 engages is formed by a piece of sound-absorbing or sound-deadening material 12 which is suitably 20 attached to the end of the lever 4. Extending upwardly from the lever 4 is a lug 13 which projects above the plane containing the cam 5, as shown in Figure 2, and is adapted to be engaged when an exaggerated movement of the lever 4 occurs by a 25 tripping device, such as a stop 14. The stop 14 is preferably integral with the sleeve 6. The tripping device or stop 14 leads the cam 5 during the rotational movement in the direction of the arrow, shown in Figure 1, and the extent to which 30 the stop 14 projects beyond the cam 5 is such that the movement imparted to the lever 4 from the tone arm during the playing period of the record is insufficient to cause the stop 14 to engage the lug 13 and during this period the cam 35 5 engages the surface 12 to return the lever 4 to its initial position in known manner. As soon, however, as the tone arm leaves the playing track and an exaggerated movement of the tone arm occurs, the lever 4 is moved a greater distance in- 40 wardly towards the axis of the turntable and in such position the lug 13 is moved into a position to be engaged by the stop 14, as shown in Figure 3. Engagement of the stop 14 with the lug 13 stops rotation of the turntable directly or it 45 may serve to move the lever 4 longitudinally in known manner to trip a brake, which in turn stops rotation of the turntable or may actuate a clutch in known manner. The engagement of the stop 14 with the lug 13 may also serve to operate 50 a switch in the circuit of an electric motor rotating the turntable or when applied to a gramophone in which automatic record changing mechanism is provided, engagement of the stop 14 with lug 13 may serve to cause an angular displacement 55

of the said lever above its pivot to cause the initiation of subsequent operations in known manner.

The surface 12 of the lever 4 may be mounted in a detachable manner so that it can be readily renewed when required, while the lug on the said lever may be formed by pressing a lug upwardly from the material of said lever. To enable the surface 12 to be adjusted if such should be necessary, it is preferable in this case to employ a disc 10 of material for the surface 12 and to support the disc on the lever 4 by an eccentric screw. In such a construction, the screw may be loosened and the disc rotated for adjustment purposes, tightening of the screw maintaining the disc in its 15 adjusted position. Other means for adjustment may of course be employed.

Where, in the above description, reference has been made to a tone arm, it will be understood that this term is intended to cover the arm carrying 20 the usual electrical reproducing device employed in radio-gramophones.

I claim:

1. In a phonograph, control apparatus comprising a rotatable member, a movable member mounted for movement toward and away from 25 said rotatable member, a cam carried by said rotatable member and rotatable therewith for engagement with said movable member to move it

away from said rotatable member upon rotation of said rotatable member, a tripping device also carried by said rotatable member disposed at a different elevation from that of said cam, and an element on said movable member adapted to be interposed in the path of rotation of said tripping device to be engaged thereby to effect predetermined control of said phonograph. 5

2. The invention set forth in claim 1 characterized by the addition of a second element on said 10 movable member arranged thereon to be contacted by said cam during rotation of said rotatable member, and characterized further in that said second element and said cam are both made of a sound-deadening material. 15

3. The invention set forth in claim 1 characterized by the addition of a second element on 20 said movable member adjustably arranged thereon to be contacted by said cam during rotation of said rotatable member, and characterized further in that said second element and said cam are both made of a sound-deadening material. 25

4. The invention set forth in claim 1 characterized in that said tripping device and said cam are so arranged on said rotatable member that said tripping device leads said cam during rotation of said rotatable member.

ARCHIBALD BURSILL.
